UNITED STATES PATENT OFFICE.

HARRY J. SILVERMAN, OF NEW YORK, N. Y.

LOOSE-LEAF BINDER.

Application filed December 15, 1922. Serial No. 607,231.

To all whom it may concern:

Be it known that I, HARRY J. SILVERMAN, a citizen of the United States, and resident of New York city, New York, have invented 5 certain new and useful Improvements in Loose-Leaf Binders, of which the following is a specification:

This invention relates to binders of improved type and is provided with adjustable 10 means whereby sheets having differently spaced perforations may be properly engaged by the posts of the binder.

Heretofore loose leaf binders have usually been provided with fixed posts adapted to 15 engage perforations of fixed spacing in the loose leaves. Different manufacturers of binders have adopted different spacings for the posts and they usually supply loose leaves to fit their own particular binder. 20 This necessitated the user purchasing the particular leaves supplied by the binder manufacturer. This lack of standardization of spacing of the perforations in the leaves has often caused considerable inconvenience 25 to users of loose leaf binders as the leaves perforated in one way were often ruled or otherwise marked in a desirable way but could not be used by owners of certain binders because the posts of their binders 30 were spaced differently than the perforations in such leaves.

My invention aims to overcome these objections and provides means whereby the posts are capable of almost universal adjustment and hence my binder can be used with leaves supplied by various manufacturers. 35

Other objects and advantages of my invention will be apparent from the following specification when read in connection with 40 the accompanying drawings, and the novel features will be defined in the appended claims.

In the drawings Fig. 1 is a perspective view of my improved binder showing a 45 multiplicity of sheets clamped therein;

Fig. 2 is a horizontal section on an enlarged scale on line 2—2 of Fig. 1;

Fig. 3 is a similar section on a lower plane as indicated by line 3—3 of Fig. 1;

Fig. 4 is a transverse section through the back of the binder showing the leaf-positioning posts and the clamps for holding the two sections of the binder firmly in engagement with the leaves;

Fig. 5 is an enlarged detail illustrating improved structural features;

Fig. 6 is a section on line 6—6 of Fig. 5;

Fig. 7 is a horizontal section on line 7—7 of Fig. 6;

Fig. 8 is a perspective detail illustrating 60 respectively a sheet-positioning post and a clamp arranged to co-act therewith;

Fig. 9 is a detail rear elevation showing 65 parts of the upper and lower members of my binder and illustrating the manner of adjusting the posts thereof to fit differently perforated leaves;

Fig. 10 is a sectional detail of a modification.

Referring first to Fig. 1 my improved 70 binder comprises an upper member 10, a lower member 12 and covers 14 and 16 hingedly secured to said upper and lower members. The upper member 10 is provided with a plurality of ears or lugs 18, 75 and the cover 14 is provided with a hinge portion 20 and a rod 22 passes through the ears and said hinge portions forming a pintle about which the cover 14 may be rocked. The lower member 12 is provided 80 with lugs 24 and the cover 16 is provided with suitable hinge portion 26 and a similar rod 28 forms a pintle about which the cover 16 can be rocked.

The lower member 12 is preferably made 85 in the form of a sheet-metal casing having a lower wall 30 and upper flanges 32 which partially enclose blocks 34 and 35. These blocks are loosely mounted in the casing and are adapted to be moved or propelled therein by 90 means of screws 36 and 38 which are in threaded engagement therewith. The inner ends of the screws 36 and 38 are provided with journal portions 40 and 42 adapted to rotate freely in a bearing block 44 secured 95 to the member 12 by a bolt or other fastening device 45. On opposite sides of the block 44 the screws 36 and 38 are each provided with suitable collars 46 to prevent endwise movement of the screws. The outer 100 ends of the screws are provided with squared ends 48 for co-action with a key 50 by which they may be rotated in order to propel the blocks 34 and 35. The block 34 carries a post 52 and the block 36 carries a similar 105 post 54. At the end of each of these posts is a screw-threaded shank 56 which engages a suitably threaded socket in the corresponding supporting block. The upper end of each post is provided with a threaded cavity 110 58 and this cavity is adapted to receive the threaded end 56 of a similar post, if the

binder is to support a great thickness of leaves or if, as illustrated, a comparatively small number of leaves are to be held in place a cap 60 having a shank 62 is secured to the top of the post.

From the above it will be clear that by turning either of the screws 36 or 38 by means for example of a suitable key as illustrated at 50 in Fig. 9, the posts can be adjusted so as to bring them into position to register with the perforations in a selected type of leaf. The inward movement of the post-carrying blocks 34 and 35 is limited by the fixed block 44 and the outward movement of said movable blocks is limited by caps 64 and 66 secured in the ends of the member 12.

I have provided improved means whereby the loose leaves can be held in clamped position between the opposed members 10 and 12 and my improved clamp is arranged to engage a corresponding post carried by the lower member in any one of its various adjusted positions. The structural details of this clamp are best shown in Figs. 4 to 8. As shown in Fig. 4 there are two such clamps, one indicated at 74 for engagement with the post 52 and the other indicated at 76 for engagement with the post 54. The clamps are of identical construction and hence a detailed description of one will suffice for both. Each clamp comprises a plate 78 which is pivoted at 80 to its corresponding supporting block 82 or 84. Each plate 82 operates within a slot 86 formed in the block and this slot is covered by a plate 88 which has an aperture 90 formed therein to permit free movement therethrough of a stud 92 which is riveted or otherwise secured to the plate 78. This stud 92 carries on its upper end a knob 94 and the portion of the stud between the plate 88 and the pivoted plate 78 is surrounded by a spring 96. This spring tends to normally hold the pivoted plate 78 in frictional engagement with the post carried by the member 12 of the binder. Reference to Fig. 5 will clearly show that the pivoted plate 78 forms an effective clamp which is adapted to grip the post at any point in its length so as to hold the member 10 in any desired spaced relationship with respect to the member 12 according to the thickness of the pack of leaves to be secured in the binder. To release the clamp it is merely necessary for the user to grasp the knob 94 and elevate it slightly so as to free the post from the grip of the pivoted clamp plate.

Each clamp is carried by a corresponding block 82 or 84, as above stated, and these blocks can be adjusted by means of lead screws 98 and 100 so as to bring the clamps into proper position for co-action with the posts carried by the blocks 34 and 35. The blocks 82 and 84 are guided with

in the walls of the member 10 and the screws for operating them are secured for rotary movement in a central block 102 in much the same manner as the screws 36 and 38 previously referred to.

From the above it is thought that it will be clear that in order to position the posts for engagement with the perforations in the loose leaves to be used, it is merely necessary to turn the feed screws 36 and 38 so as to bring the posts 52 and 54 into register with the perforations in the leaves. After this has been accomplished the screws 98 and 100 are operated so as to bring the clamps into position to engage the posts. When this has been done the sheets will be placed in the binder with the posts projecting through the perforations thereof and the member 10 will be pushed down to tightly engage the topmost sheet and thus permit the clamps to secure a frictional bite on the posts and thus hold the member 10 securely in proper spaced relationship to the member 12.

If it is desired to subsequently use sheets which are perforated differently than the ones formerly used it is merely necessary to turn the screws by means of a suitable key as illustrated in Fig. 9 so as to move the posts from the full line position, for example, to the dotted line position in order to adjust the binder for use with sheets perforated to correspond with the dotted lines as indicated in this figure.

If desired, I may provide in the upper clamping member 10 a single lead screw as illustrated at 68 having right-hand threads as at 70 on one end and left-hand threads as at 72 on the other end as shown in Fig. 10, so that by turning the single lead screw both blocks 82 and 84 can be simultaneously moved in either an inward or an outward direction. The same arrangement may be used for the blocks 34, 35 for the posts.

Though I have described with great particularity the details of construction of the particular embodiment of the invention herein shown, it is not to be construed that I am limited thereto as changes in arrangement and substitution of various expedients may be resorted to without departing from the spirit and scope of the invention as defined in the appended claims.

What I claim is:

1. A loose leaf binder including a pair of opposed members between which the leaves are adapted to be held, posts mounted for adjustable movement in one of said members, clamps carried by the other member, and means for moving said clamps to position them for proper co-action with the posts in any selected position of said posts.
2. A loose leaf binder having posts adapted to engage perforations in leaves, means for adjusting the position of said posts for

engagement with sheets having perforations of a selected spacing, clamping means arranged to co-act with said posts and means for moving said clamping means to position for co-action with said posts.

3. A loose leaf binder including a pair of opposed members between which the leaves are adapted to be held, posts carried by one of said members for positioning the leaves in the binder, means for moving at least one of said posts to vary their spacing, clamping means carried by the other member and means for moving the clamping means to position for engagement with any selected position of said posts.

4. A loose leaf binder comprising a pair of opposed members between which the leaves are clamped, one of said members having a pair of movable post-carrying blocks guided therein, means for propelling said blocks, the other member having clamp-carrying blocks and means for propelling the clamp-carrying blocks in order to position the clamps thereof for engagement with the posts carried by said post-carrying blocks.

5. A loose leaf binder comprising a pair of opposed members between which the leaves are clamped, one of said members having a pair of movable post-carrying blocks guided therein, feed screws for propelling said blocks, the other member having clamp-carrying blocks and feed screws for propelling the clamp-carrying blocks in order to position the clamps thereof for en-

gagement with the posts carried by said post-carrying blocks.

6. A loose leaf binder having opposed members between which the leaves are clamped, one member having posts for positioning the sheets in the binder and the other member having clamps adapted to engage said posts to hold leaf packs of different thicknesses between said members and separate means for moving said posts and said clamps to position them for proper engagement with sheets perforated according to a selected spacing.

7. A loose leaf binder having opposed members between which the leaves are clamped, one member having movable posts for positioning the sheets in the binder and the other member having movable clamps adapted to engage said posts to hold leaf packs of different thickness between said members each of said clamps comprising a spring-pressed pivoted plate arranged to normally exert a friction grip on one of said posts, means for manually releasing the grip of the clamps to permit the movement of one of the aforesaid members relative to the other in order to allow the insertion or removal of leaves, and separate means for moving said posts and said clamps to position them for proper engagement with sheets perforated according to a selected spacing.

In witness whereof, I have hereunto signed my name.

HARRY J. SILVERMAN.
